UNITED STATES PATENT OFFICE.

CHARLES L. HOUSEHOLDER, OF WASHINGTON, DISTRICT OF COLUMBIA.

DISPLAY STAND FOR DISCHARGE CERTIFICATES.

1,418,261.

Specification of Letters Patent. Patented May 30, 1922.

Application filed June 5, 1919, Serial No. 302,073. Renewed November 3, 1921. Serial No. 512,575.

To all whom it may concern:

Be it known that I, CHARLES L. HOUSEHOLDER, a citizen of the United States, and a resident of Washington, District of Columbia, have invented certain new and useful Improvements in Display Stands for Discharge Certificates, of which the following is a specification.

This invention relates to an improvement 10 in display stands or cabinets, and one of the principal objects thereof is to provide a stand for the attractive display of the certificates of honorable discharge of men in military or naval service.

Another object of the invention is to provide a frame for receiving the discharge certificate, such frame being rotatably mounted upon a base in such a manner that it may be turned in various positions to be 20 viewed from different angles.

A further object of the invention is to provide an improved display stand of the class described which will be exceedingly simple, durable, and efficient in operation 25 and which may be manufactured at small cost.

With these and other objects in view which will become apparent as the description proceeds, the invention resides in the 30 construction, combination and arrangement of parts hereinafter more fully described and claimed, and illustrated in the accompanying drawing, in which like characters of reference indicate like parts throughout 35 the several figures, of which

Figure 1 represents an elevational view of a stand constructed according to my invention;

Figure 2 represents a vertical sectional view therethrough, taken at right angles to Figure 1; and

Figure 3 represents a top plan view of the stand, the cap piece being removed.

Referring more particularly to the drawing, the stand includes a rectangular frame 45 consisting of side pieces 5 and end pieces 6, the upper end piece being longitudinally slotted as at 7, in order that the plates of glass 8 may be inserted into the frame and 50 in order that the discharge certificate, not shown, may be put in place between the plates of glass. The edges of the glass are supported in a groove 9 cut in the inner face of the two side pieces and the lower 55 end piece. In this manner the glass is removably retained in position in the frame.

A cap piece, indicated at 10, is provided adjacent its ends with dowels 11, which fit in the recesses 12 within the cross pieces 6 so that the cap is removably disposed upon 60 the frame. The cap piece may be removed to insert the discharge certificate and may be then replaced to add a finish to the frame and to prevent accidental loss of the glass or the certificate from the frame. The 65 grooves for receiving the glass are wide enough to snugly engage the edges of the glass when the glass plates are separated the thickness of a sheet of relatively heavy paper, and thus when the cap piece is in 70 place the discharge certificate will be snugly held and will be protected from dust and dirt.

A standard 13 supports the frame, being provided at its upper end with a pin 14 engaging in a recess in the frame, portions of the standard adjacent to the pin 14 being shouldered at 15 to provide a steady and strong support for the frame. The standard is rotatably mounted in a base 16, which, 80 similar to the standard, is of an attractive appearance, and this base is centrally provided with an opening through which the lower end of the standard projects, the shoulder 17 on the standard resting upon 85 the top of the base. Below the shoulder 17 the standard is provided with a reduced portion 18, fitting into the upper end of the opening through the base, and this reduced portion is again reduced, as at 19, to extend through the lower portion of the opening, a shoulder 20 in the shank being thus formed which rests against the shoulder 21, formed at the junction of large and small 90 portions of the opening provided in the base. The lower end of this opening is counter-sunk, as at 22, to receive a screw 23 which screws into the lower end of the stem of the standard. The screw extends through a washer 24 and is headed, the head being 100 of a configuration to conform to the counter-sunk end 22, the stem of the standard rotatably fits the opening of the casing whereby the standard, and with it the frame, may be rotated to assume various positions, 105 whereby the certificate may be viewed from various angles.

The cap piece, together with other portions of the frame may be suitably decorated with various emblems designating divisional 110 corps or Army emblems and the branch of service, or may be otherwise attractively or-

namented. The entire stand may be painted mahogany or any other suitable color, as desired.

Although I have described the preferred embodiment of my invention I may desire to make such changes in construction, combination and arrangement of parts thereof as to not depart from the spirit of the invention and the scope of the appended claim.

10 I claim:

A display stand comprising a frame rectangular in shape and having its upper end open and having the upper ends of its side members beveled, the inner faces of the side members and the bottom member of the

frame being grooved, panes of glass slidably engaged within the grooves in said side members and set within the groove in said bottom member, said panes of glass being spaced apart whereby to accommodate therebetween a sheet to be displayed, a top member for said frame having beveled ends conformingly engaging the beveled upper ends of said side members and being provided with a slot through which the panes of glass extend, and a cap piece having the same length as said top member and carrying dowel pins engaged within sockets in said top member.

CHARLES L. HOUSEHOLDER.
